Geo. P. Kimmel, Attorney

Patented Mar. 6, 1923.

UNITED STATES PATENT OFFICE.

EDMUND H. MORRISSEY, OF ALTON, ILLINOIS.

ATTACHMENT FOR SHOE-STITCHING MACHINES.

Application filed March 21, 1921. Serial No. 454,065.

To all whom it may concern:

Be it known that I, EDMUND H. MORRISSEY, a citizen of the United States, residing at Alton, in the county of Madison and State of Illinois, have invented certain new and useful Improvements in Attachments for Shoe-Stitching Machines, of which the following is a specification.

The invention relates to improvements in attachments for shoe stitching machines, and more particularly to a type of the same adapted for use in connection with shoe repair operations on such machines.

The principal object of the invention is to provide for a novel form of presser foot construction, and one especially adapted for effective operation during the rewelting of old shoes whereby the welt is applied to the shoe in a smooth uniform manner, and is held in such condition throughout the stitching or sewing operation.

Another object of the invention is to provide for a presser foot of the character mentioned, and one embodying an extremely efficient guiding means for a welt strip, whereby the same is pressed firmly onto the surface of the sole, which is to be attached thereto, and is maintained in proper position and against buckling during the stitching or sewing operation.

A further object of the invention is to provide for a combined presser foot and welt guide of the type set forth, and one which is especially designed to closely follow curved outlines or configurations of shoe uppers immediately adjacent to or above the points of connection of the same with the sole portion of a shoe.

With the foregoing and other objects in view, the invention resides in the certain novel and useful construction of the class mentioned which will be hereinafter more fully described, set forth in the appended claims, and illustrated in the accompanying drawing, in which:—

Figure 1 is a perspective view of the preferred embodiment of the invention,

Fig. 2 is a vertical transverse section through the same, and,

Fig. 3 is a bottom plan view thereof.

Referring to the drawing, the numeral 10 indicates the shank portion of the improved form of presser foot, the same being circular in cross section and tapering downwardly to provide a portion 11 of a reduced diameter,

connecting the upper face of the foot portion 12 at one end and to one side of the longitudinal center thereof. The upper end of the shank portion 10 is formed with a circular bore to provide a socket 13 for engagement on the free end of a presser foot bar *a* of a sole stitching or sewing machine, the latter being preferably of a straight needle and awl type of shoe stitcher, suitable threaded openings 14 being formed laterally through the wall of the shank socket for the reception of set-screw fastenings (not shown) by means of which the presser foot is to be secured in operative position on the bar *a*.

The foot portion 12 of the presser foot is preferably cast in one piece with the shank portion 10, and consists of an elongated body of arcuate contour having its opposite side walls spaced on parallel curved lines whereby the working inwardly curved side wall 15 thereof is conformed to by the curvature of the shoe upper during the application of a welt strip to the sole portion of the shoe. The heel portion of the foot 12 is undercut to provide an inwardly extending curved groove 16 gradually decreasing in width inwardly and which opens into the rear wall portion of a vertically extending substantially elliptical opening 17, while the toe portion thereof is formed with the horizontal elongated slot or recess 18 opening into the front wall of the vertical opening 17 and it is disposed in alinement with the opposed end of the groove 16, but in a plane slightly above the same. The vertically disposed opening 17 of the foot has its rearward portion or wall, as at 19, extending upwardly for a slight distance of the front wall of the forward portion of the reduced end 11 of the shank 10, the latter being curved in a rearward direction from its point of connection with the foot portion, so that the socket 13 formed at the upper end thereof lies substantially in a plane vertically of the heel portion, which arrangement gives clearance at the forward portion of the leg or shank 10 for the proper vertical reciprocation of the needle bar *b*, which operates in parallel relation thereto, the needle *c* of the bar *b* being adapted to operate vertically through the opening 17 during the actuation of the latter. The forward lower edge of the toe portion of the foot 12 is slightly bevelled or curved, as at 20, in an upward direction,

whereby to admit of the free passage thereunder of the adjacent portion of the shoe to be welted and sewed.

In the use of a presser foot and welt guide thus provided, the socket 13 is engaged on the free end of a presser foot bar *a*, and is secured in desired adjusted position thereon by means of a set-screw, as shown in Fig. 2, with the opening 17 thereof disposed below the point of the needle *c* depending from the needle bar *b* and which operates in a plane parallel to the presser foot bar *a*. The free end of a welt strip *d* is now passed inwardly through the slot 18 in the toe portion of the foot 12 and is trained across the lower end of the opening 17 and projected inwardly through the groove 16 in the heel portion, and the machine will now be ready for the weltling operation. In applying the welt strip *d* to the upper face of the extended portions of the sole portion of the shoe to be rewelted, the sole extension (not shown) is inserted beneath the lower face of the presser foot so that the welt strip *d* carried thereby is pressed firmly upon the surface thereof for the sewing operation, and as the shoe is turned for the laying on of the welt entirely around the sole extension, the outer side wall of the upper portion of the shoe will contact the inwardly curved face 15 of the foot portion 12, whereby the welt strip *d* will be properly applied, and held uniformly smooth throughout the sewing or stitching operation, and is otherwise securely held against buckling under the thrust of the awl or needle at all times.

Having thus fully described the invention, what is claimed, is:-

1. A presser foot for use in connection with the reweltling of shoes comprising a curved foot portion, a shank integral with said foot portion intermediate the ends of the latter, said foot portion and lower part of the front of the shank provided with a vertically disposed opening, said foot portion further provided with a horizontally disposed slot and a curved groove, said groove formed in the lower face of the heel

of the foot portion and extending inwardly and opening in the rear wall portion of 50 said opening, and said slot formed in the toe of the foot portion and opening into the front wall portion of said opening, said slot disposed in alinement with the opposed end of said groove and in a plane slightly 55 above the same.

2. A presser foot for use in connection with the reweltling of shoes comprising a curved foot portion formed intermediate its ends with a vertical opening and with a 60 horizontal slot in the toe thereof communicating with said opening and further provided in the lower face of the heel thereof with a curved groove communicating with said opening, said groove gradually decreasing 65 in width toward said opening.

3. A presser foot for use in connection with the reweltling of shoes comprising a curved foot portion formed intermediate its ends with a vertical opening and with a 70 horizontal slot in the toe thereof communicating with said opening and further provided in the lower face of the heel thereof with a curved slot communicating with said opening, said groove gradually decreasing in 75 width toward said opening, said slot disposed in alinement with the opposed end of said groove and in a plane slightly above the same.

4. A presser foot for use in connection 80 with the reweltling of shoes comprising a foot portion of arcuate contour provided with a vertically disposed opening substantially elliptical in section and further provided at the toe thereof with a horizontally 85 disposed slot communicating with the front of said opening, said foot portion further having the lower face of the heel thereof formed with a curved groove communicating with the rear of said opening and arranged slightly below the plane of said slot, and a shank integral with said foot portion intermediate the ends of the latter.

In testimony whereof, I affix my signature hereto.

EDMUND H. MORRISSEY.
